(57) **CLAIM**

The ornamental design for the medical instrument, as shown and described.

DESCRIPTION

FIG. 1 is a top plan view of the medical instrument with a depressible button in a raised position and a rotatable nozzle in a vertically and horizontally centered position;

FIG. 2 is a bottom plan view of the medical instrument with the nozzle in the vertically and horizontally centered position;

FIG. 3 is a right elevation view of the medical instrument with the button in the raised position with the nozzle in the vertically and horizontally centered position;

FIG. 4 is a left side elevation view of the medical instrument with the button in the raised position and the nozzle in the vertically and horizontally centered position;

FIG. 5 is a front elevation view of the medical instrument with the nozzle in the vertically and horizontally centered position, where the broken lines showing portions of a medical instrument are included for the purpose of illustrating environmental structure and form no part of the claimed design.

FIG. 6 is a rear elevation view of the medical instrument with the button in the raised position and the nozzle in the vertically and horizontally centered position;

FIG. 7 is a perspective view of the medical instrument viewed from the rear and right of and above the medical instrument and with the button in the raised position and the nozzle in the vertically and horizontally centered position;

FIG. 8 is a perspective view of the medical instrument viewed from the front and left of and below the medical instrument and with the button in the raised position and the nozzle in the vertically and horizontally centered position;

FIG. 9 is a left side elevation view of the medical instrument with the button in a lowered position and the nozzle in the vertically and horizontally centered position;

FIG. 10 is a top plan view of the medical instrument with the button in the lowered position and the nozzle in the vertically and horizontally centered position;

FIG. 11 is a perspective view of the medical instrument viewed from the rear and right of and above the medical instrument and with the button in the lowered position and the nozzle in the vertically and horizontally centered position;

FIG. 12 is a right elevation view of the medical instrument with the button in the raised position with the nozzle in a vertically raised and horizontally centered position;

FIG. 13 is a right elevation view of the medical instrument with the button in the raised position with the nozzle in a vertically lowered and horizontally centered position;

FIG. 14 is a top plan view of the medical instrument with the button in the raised position and the nozzle in a vertically centered and first horizontally displaced position; and,

FIG. 15 is a top plan view of the medical instrument with the button in the raised position and the nozzle in a vertically centered and second horizontally displaced position.
